OPHTHALMIC LENS HARDENING APPARATUS

Stanley Kirk, Wantagh, N.Y., assignor to Kirk Optical
Lens Co., Inc., New York, N.Y.

Filed Dec. 14, 1970, Ser. No. 26,479

Term of patent 3½ years

Int. Cl. D16—08

U.S. Cl. D57—1

FIG. 1

FIG. 3

FIG. 2

FIG. 4

FIG. 1 is a perspective view of an ophthalmic lens hardening apparatus showing my new design;

FIG. 2 is a front view;

FIG. 3 is a top plan view; and

FIG. 4 is a side view.

The rear of the ophthalmic lens hardening apparatus, not shown, is plain and free of ornamentation.

I claim:

The ornamental design for an ophthalmic lens hardening apparatus, substantially as shown and described.
